UNITED STATES PATENT OFFICE.

ROBERT H. SALMONS, OF ROCHESTER, NEW YORK.

APPARATUS FOR RACKING LIQUIDS.

SPECIFICATION forming part of Letters Patent No. 694,668, dated March 4, 1902.

Application filed January 16, 1902. Serial No. 89,998. (No model.)

To all whom it may concern:

Be it known that I, ROBERT H. SALMONS, a citizen of the United States, residing at Rochester, in the county of Monroe and State of New York, have invented a new and Improved Racking Apparatus, of which the following is a specification.

The object of my invention is to provide means whereby the beer or other liquids to be racked into the keg or package for delivery to the retail dealer may be racked under any desired pressure and also to provide means for preventing the accumulation of what is termed "overflow" or "rest" beer.

15 A further object of my invention is to provide means whereby there may be secured any desired difference in pressure between the gas in the keg to be filled and the pressure under which the beer or other liquid is forced 20 into such keg. It is oftentimes desirable to vary this difference of pressure and to rack the beer under different pressures.

25 My invention may be used in connection with a gravity system for filling the kegs or not, as desired.

The accompanying drawings, illustrating my invention, are as follows:

Figure 1 is a side view of the apparatus complete. Fig. 2 is a vertical sectional view 30 taken along the dotted line xy of Fig. 1 looking from the right, all parts to the right of such dotted line being removed. Fig. 3 is an enlarged vertical sectional detail view through the center of one of the valves v' . Fig. 4 is 35 a diagrammatic view showing the connection of the racking apparatus to the chip-cask and pressure-pump.

Similar letters refer to similar parts throughout the several views.

40 Referring to Figs. 1 and 2 of the drawings, r is the pressure-bock, provided with a suitable pressure-gage g and suitably connected, as will be explained later, with a source of supply in which there is maintained any desired constant pressure of gas or air which is to be forced into the keg to be filled before the beer is racked into such keg. Connected with and located beneath this pressure-bock r suitable cut-off valves v are seen and making connection therewith in such a way that the opening of such valves admits the gas or air from the pressure-bock r down through

the cut-off chambers s , and thence through the hose or pipes p , connected to the lower end thereof, and through the coupling-faucets k 55 into the kegs b through any one of the well-known bushings—such, for instance, as that described in the patent to Stahl, No. 600,501, March 8, 1898—arranged to coöperate with these coupling-faucets k in the manner clearly 60 described in such patent and already so well known in the art as to call for no further description. From the beer-bock r' , which is supported, as seen, by suitable brackets t and into which the beer is forced from the chip-cask C in the manner yet to be explained, there extend downward a series of connections terminating in suitable cut-off valves v^3 , and from each of which a hose or pipe p' extends downward, terminating at its lower end in 70 the coupling-faucets v' , arranged to coöperate with bushings located at the lowest points in the ends of the kegs b to be filled, such faucets v^4 coöperating with their bushings in the manner already described in connection with the coupling-faucets k . The cut-off chambers s open at their upper ends into suitable pressure-release valves w of any of the well-known constructions. Suitable sight-chambers s' are seen extending upward from 80 this supply-bock r' , having faucets c at their upper ends in order that the condition of the liquid in the supply-bock may be readily seen. When desired, a suitable faucet c' may be located also at the upper side of 85 the supply-bock r' . A suitable valve v^5 is seen extending downward from the supply-bock r' , arranged, as indicated, to receive connection with a hose or other pipe in order that the supply-bock r' may be washed out each 90 time before it is used in the process of racking. The pressure at which the gas or air confined within the kegs b will be allowed to escape is determined, of course, by the angular adjustment of the face-plates to these pressure-valves w , and by means of which the gas or air in the kegs b may be retained therein at any desired pressure, which may be the same for all the kegs b , or it may be different for each keg b , as desired.

Within each cut-off valve-chamber s there is located a float-valve v' , the weight of which is such that any foam rising from the beer in the kegs b through the hose p into such cut-

off chambers s will not lift this valve v' ; but any beer that is forced through the hose p into these chambers s will serve to lift these valves v' against their seats at the top of the 5 cut-off chambers s . The details in the construction of the valve-chambers and valves will be more fully understood by reference to Fig. 3, in which a and a' constitute the top and bottom castings, which, by means of the 10 rods a^5 , are firmly clamped against the packing-rings a^2 , located at the top and bottom of the glass cylinder s . The float v' is formed with a suitable top piece a^4 , arranged to cooperate with the valve-seat a^3 at the under 15 side of the top plate a in such a way that as the float v' is raised it effectually closes the opening at the upper end of the cut-off chamber, thereby preventing any beer from escaping through the opening in the top piece a^3 20 of this cut-off chamber.

Refer now to Fig. 4. C represents a chip-cask, which is connected, as indicated, with the supply-bock r' through the sight-chamber s^2 , secured to the bock r' and having at its 25 lower end a suitable cut-off valve v^6 , leading into the two-way coupling-piece p^2 , to which the pipe leading from the chip-cask is directly connected. This pipe leading to the chip-cask may make connection therewith at any suitable 30 point low enough to draw off all the beer that it is customary to withdraw from the chip-cask before recharging, or it may extend upward within the chip-cask to a similar point. The chip-cask C is also provided with a pressure-gage g' . S' represents diagrammatically the cylinder of a pressure-pump, the piston working in which is connected by means of the piston-rod n with the piston in the steam-cylinder S . From the pump-cylinder S' there 35 extends a pipe p^3 , leading to the pressure-bock r and making connections also, by means of the pipe p^5 , with the chip-cask C at its upper end. This pipe p^3 is connected by means of a short pipe p^4 with a suitable diaphragm-regulator d' the operation of which, by means 40 of the bell-crank lever t' and the connecting-rod t^2 , is caused to vary the supply of steam through the valve v^7 , operated by such mechanism in the supply-pipe p^7 in the well-known 45 manner.

The parts just above described are intended only as a diagrammatic illustration of any one of the well-known automatic pressure-regulating pumps by means of which any desired pressure may be maintained in the pressure-bock r , as indicated by the gage g , and also in the chip-cask C , as indicated by the gage g' .

In using my racking apparatus the kegs b 60 are placed in position substantially as shown in Figs. 1 and 2 of the drawings, and connection is made thereto by means of the pipes p' and p in the manner already described and well known in the art, the coupling-faucets 65 k and v^4 being turned so as to open the valves in the bushings in the kegs b , in which they are respectively inserted. The faucets k are

then opened, while the faucets v^4 remain closed. Then the valves v are opened, whereupon the air or gas under pressure in the bock r is forced into the kegs b , filling the same and establishing therein a pressure determined by the adjustment of the release-valves. Of course just before the filling of any kegs b the corresponding regulators w 70 are set by means of the rotatable disks seen at the front sides thereof to the pressure against which it is desired to rack the beer or other liquid. Then when the kegs b have been filled with the gas or air under pressure 75 the cut-off valves v are closed and the coupling-faucets v^4 are opened and at the same time also the cut-off valves v^3 , unless they are already open. Then the beer from the bock r' is forced into the kegs b through the 80 pipes p' and the connections between such pipes and the kegs b until the kegs are filled with beer, and the beer rises through the pipe p into the cut-off chambers s sufficiently to 85 lift the float-valves v' against their seats a^3 90 (see Fig. 3) at the upper end, the chambers s containing such valves thus effectually preventing any further rising of the beer in the pipe p . Then the coupling-faucets v^4 are 95 closed and then removed from the bushings in which they have been inserted, serving also at the same time to close the valves in such bushings. The coupling-faucets k may then be closed and such faucets removed from the bushings, and during such removal, it will 100 of course be understood, the valves in the bushings in which they were inserted are closed in the well-known manner.

By the use of my apparatus I am able to prevent the accumulation of overflow or rest 105 beer, as in the filling of any keg the beer that in the filling of the preceding keg had risen in any pipe p and in its cut-off chamber s is securely held therein after the coupling-faucet k has been closed and before the removal 110 thereof from the bushing in which it was inserted, because as the coupling-faucet k is inserted in the bushing of the keg and then turned so as to open the valve of such bushing and then the coupling-faucet k opened 115 the beer that was in the pipe p and in this cut-off chamber s is forced immediately into the keg b . By the use of my apparatus also I am enabled to rack under any desired pressure by means of apparatus operating independently of the source of supply of the gas or air under pressure.

What I claim is—

1. In a system for racking liquids, a chip-cask or source of supply for such liquids, a 125 source of gas or air under practically constant pressure connected with such chip-cask, a supply-bock for such liquid connected with such chip-cask, a pressure-bock connected to such source of gas or air under pressure, two 130 or more kegs to be filled, pipes leading from the supply-bock to such kegs and containing therein also cut-off valves, pipes leading from such pressure-bock also to the kegs to be

filled and also containing cut-off valves, adjustable and automatically-operating pressure-relief valves located in such last-named pipes and between the cut-off valves therein 5 and the pressure-bock to which they are connected, each of such automatically-operating pressure-valves independently adjustable at different pressures, and also valve-chambers containing floating check-valves arranged to 10 be closed by such liquid only as it rises in such valve-chamber, such valve-chambers and valves also located in such last-named pipes and between the cut-off valves therein and such adjustable and automatically-oper- 15 ating pressure-relief valves.

2. In a system for racking liquids, a source of supply for such liquid under pressure, a source of gas or air under practically constant pressure, a pressure-bock connected to such 20 source of gas or air, two or more kegs to be filled, means for connecting such kegs to be filled to such source of liquid under pressure, a pipe leading from such pressure-bock to each of such kegs and containing therein the 25 following elements and in the order named commencing with such pressure-bock: a cut-off valve, an adjustable and automatically-operating pressure-relief valve, a check-valve arranged to be closed by the liquid as it rises 30 in such pipe, and a cut-off valve located in

such pipe as near as may be at the point where such pipe makes connection with the keg to be filled.

3. In a system for racking liquids, in combination with a keg to be filled and means 35 for supplying liquid thereto under pressure, means for first charging such keg with gas or air under pressure and then forcing the liquid into such keg under pressure greater than that of the gas or air in such keg, thus forcing 40 such air or gas out of such keg and allowing it to escape into the open air through suitable valve-controlled tubing, means for automatically checking the inflow of liquid to such keg as such liquid rises in such tubing, and means for disconnecting such tubing from such keg and retaining the liquid that has arisen therein under a pressure practically the same as that against which the liquid is racked or forced into such keg until 45 50 such tubing is connected to the next succeeding keg, and means for forcing such liquid contained in such tube into such next succeeding keg and subjecting the same to the pressure of the gas or air with which such 55 next succeeding keg is charged.
